US00D957022S

(12) **United States Design Patent** (10) **Patent No.:** **US D957,022 S**
Yao (45) **Date of Patent:** **** Jul. 5, 2022**

(54) **WORK LAMP**

(71) Applicant: **YUYAO YUCHANG ELECTRICAL APPLIANCE CO., LTD.**, Zhejiang (CN)

(72) Inventor: **Pinfeng Yao**, Zhejiang (CN)

(73) Assignee: **YUYAO YUCHANG ELECTRICAL APPLIANCE CO., LTD.**, Zhejiang (CN)

(**) Term: **15 Years**

(21) Appl. No.: **29/756,349**

(22) Filed: **Oct. 27, 2020**

(30) **Foreign Application Priority Data**

Jun. 2, 2020 (CN) 202030268531.5

(51) LOC (13) Cl. **26-05**

(52) U.S. Cl. ..... USPC **D26/62**

(58) **Field of Classification Search**

USPC D26/24, 60, 61, 62, 63, 64, 65, 66, 67, D26/68, 72, 79, 37, 43, 46, 48, 49, 50

(57) **CLAIM**

The ornamental design for a work lamp, as shown and described.

DESCRIPTION

FIG. 1 is a perspective view of a work lamp showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof; and,

FIG. 8 is a perspective view thereof, showing the status while in use.

The broken lines illustrate portions of the work lamp that form no part of the claimed design.

1 Claim, 7 Drawing Sheets
